HEATING TRAY

Lawrence Lerner, White Plains, N.Y., assignor to Michael Saphier Associates, Inc., New York, N.Y., a corporation

Filed May 18, 1961, Ser. No. 65,219

Term of patent 3½ years

(Cl. D81—10)

FIG. 1

FIG. 2

FIG. 1 is a front perspective view of a heating tray showing my new design; and

FIG. 2 is a rear perspective view thereof.

The fragmentary table top shown in broken lines in FIGS. 1 and 2 is included for illustrative purposes only.

My design for the heating tray disclosed is characterized by the contrasting leading edge panels and knob encased by the downwardly projecting portion of the frame, all as shown.

I claim:

The ornamental design for a heating tray, substantially as shown and described.
